(57) CLAIM

An ornamental design for a vehicle lower front bumper cover, shown and described.

DESCRIPTION

FIG. 1 is a top plan view of a vehicle lower front bumper cover;

FIG. 2 is a bottom plan view of the vehicle lower front bumper cover;

FIG. 3 is front elevational view of the vehicle lower front bumper cover;

FIG. 4 is a left side elevational view of the vehicle lower front bumper cover;

FIG. 5 is a right side elevational view of the vehicle lower front bumper cover; and,

FIG. 6 is a perspective view of the vehicle lower front bumper cover.

The broken lines and the lighter contrast areas shown throughout the drawing are shown for illustrative purpose only and form no part of the claimed design.
